UNITED STATES PATENT OFFICE.

CLARK F. RIGBY, OF BUTLER, PENNSYLVANIA, ASSIGNOR OF ONE-FOURTH TO SAMUEL J. ELLIOTT, OF PITTSBURGH, PENNSYLVANIA, AND ONE-FOURTH TO FRED R. VAN LEAR, OF CHAMBERSBURG, PENNSYLVANIA.

ELECTRIC CONTROL FOR DRILLING ENGINES AND MOTORS.

Application filed May 29, 1924. Serial No. 716,599.

To all whom it may concern:

Be it known that I, CLARK F. RIGBY, a citizen of the United States, residing at Butler, in the county of Allegheny and

5 State of Pennsylvania, have invented a new and useful Improvement in an Electric Control for Drilling Engines and Motors, of which the following is a specification.

This invention relates to an electric control for drilling engines.

10 While internal combustion engines provide the most compact and most convenient source of power for drilling, as for various other purposes, they are not normally susceptible of use to actuate a well drilling rig, because they operate at uniform speed and deliver uniform power. That is, an internal combustion engine does not accommodate itself automatically to widely varying conditions. In drilling by the standard or cable system, as is well known, the motion is intermittent. That is, a string of heavy tools is lifted slowly and dropped quickly. This operation is performed by means of a

15 walking beam, which carries the string of tools at one end thereof, and which is actuated by an eccentric connection at its other end with the band wheel of the rig.

20 Since the drilling motion is irregular, comprising a slow upward pull and a quick dropping of the tools, it is necessary that the moving parts of the drilling engine be operated by the weight of the tools during the dropping motion. Otherwise the engine 25 would be acting as a brake on the tools during their fall, and would thus greatly impair the efficiency of the operation. While steam engines accommodate themselves automatically to this motion, exhaust-

30 ing power to permit the weight of the tools to drag their moving parts during the portion of the drilling cycle in which the tools are dropped, internal combustion engines, as previously stated, do not act automatically 35 in such manner.

It has been attempted to regulate the speed of an internal combustion engine in accordance with the drilling motion by mechanical means. While operative, such means have,

40 however, not proven completely satisfactory. The object of the invention is, therefore, to provide electrical means and connections, which may be controlled automatically

45 from a moving part of the drilling rig to regulate the speed of an internal combustion engine in accordance with the drilling motion.

50 In the accompanying drawings Figure 1 is a side elevation of the elements of a drilling rig pertinent to the present invention, and showing the arrangement of the invention; Figure 2 is a detail view showing the elements of the device which are in immediate conjunction with the internal combustion engine of the drilling outfit; Figure 3 is a detail elevation showing a preferred arrangement of electrical connections with a moving part of the drilling rig; Figure 4 is an elevation of pertinent parts of a drilling rig, showing modified 55 connections with a moving part of the rig; Figure 5 is a plan view of the same; Figure 6 is a detail side elevation of a modified form of connection with a moving part 60 of the drilling rig; and Figure 7 is a front 65 elevation of the same modification.

70 In the drawings the reference numeral 1 indicates the Samson post of the rig upon which is pivotally mounted the walking beam 2. At one end 2a of the walking beam are the elements for suspending the drilling line, indicated generally by the reference numeral 3, and at the other end is a pitman 4 connected with an eccentric 5 on the shaft 6 of a band wheel 7. The 75 internal combustion engine, indicated generally by the reference numeral 3 is connected with the band wheel by any suitable connection 9.

80 The carburetor 10 of the internal combustion engine, with particular reference to Figures 1 and 2 of the drawings, is provided with a throttle 11 to which connect jointed operating rods 12 and 13. Rod 13 is pivotally mounted at 14. During the 85 running of the engine the throttle is normally held in a fixed position by means of a coiled spring 15, which is connected with arm 13 on one side of the pivotal point thereof, and an adjustable stop 16 mounted in a frame 17 on the other side of the pivotal point of the operating rod 13. A solenoid 18, disposed in close proximity to the operating arm or rod 13, is arranged when energized to open the throttle of the engine 100 to a greater extent than that for which it

is normally set. Connected with the solenoid 18 is a circuit wire 19 leading to the terminal post 20 of a storage battery 21. A second circuit wire 22 leads to a contact bar 23, which is mounted on one of the band wheel posts 24. A circuit wire 25 leads from the terminal post 26 of the battery to a contact bar 27 also mounted on the band wheel post 24.

- 10 As shown in Figures 1 and 3 of the drawings, a hub plate 28 of conducting material is carried by the band wheel 5 to rotate therewith. Contact bar 27 bears against the periphery of the plate, which is of conducting material throughout. Contact bar 23 bears against the face of the disk 28, in such manner that the rotation of the disk forms with the contact bar a path concentric with the center of the disk.
- 15 20 Forming an arc equal to a semicircle along this path is a plate 29 of insulating material.

In conducting the drilling operation the band wheel 5 is brought to proper position prior to its connection to the pitman 4, so 25 that the contact bar 23 bears upon the insulating plate 29 during the down stroke of the end 2^a of the walking beam 2 which supports the string of tools, and bears against the face of the disk 28 itself during the up 30 stroke of that portion of that end of the walking beam which supports the tools.

The result of the arrangement is that the solenoid 18 is energized during the upward movement of the end 2^a of the walking beam, 35 while the tools are being lifted in the well. The energization of the solenoid 18 causes it to attract the end 13^a of the pivoted arm or rod 13. This motion transmitted through the operating arm 12 opens the throttle 11 40 of the engine. The engine is thus enabled to deliver greater power for raising the tools.

When the contact bar 23 rides upon the insulating plate 29, during downward movement of the end 2^a of the walking beam, the circuit completed between bars 23 and 27 by the disk 28 is broken, and solenoid 18 deenergized. Upon deenergization of the solenoid 18, the coiled spring 15 acts upon 45 the arm 13 to move such arm as far as is permitted by the stop 16, thus partially closing the throttle 11 of the engine. This decreases the power output of the engine to such extent that the weight of the tools determines the action of the moving parts of 50 the engine, and the engine does not exert such power against the fall of the tools as to unduly retard the same.

Figures 4 and 5 illustrate a modified arrangement of contact bars, and means for electrically connecting the same, other portions of the mechanism being identical with those shown in Figure 1. As shown in these latter figures, contact bars 31 and 32 are 60 mounted on a post 33 adjacent the band

wheel 7. The band wheel 7 carries on its face a plate 34 of conducting material, which is approximately semicircular, and which is disposed concentrically with the shaft 6 of the band wheel. The bars 31 and 32 are 70 parallel to each other and are sufficiently close together that they are both in contact with the conducting band 34 during approximately the same period of time.

During the up stroke of the end 2^a of the walking beam 2, both of the contact bars 31 and 32 are in contact with the conducting band 34, so that the circuit is completed through the conducting band and the solenoid 18 energized. During the down stroke 80 of the end 2^a of the walking beam, contact bars 31 and 32 may ride upon the non-conductive material of the band wheel proper or may be completely out of contact with the face of the band wheel.

85 In the modification illustrated in Figures 6 and 7 of the drawings, contact bars 35 and 36, mounted on a post 37, are electrically connected by a band 38 of conductive material set into the periphery of a wheel 39 secured to the shaft 6 of the band wheel, during a portion of each revolution of the band wheel.

The action of the mechanism with this modification of the device is exactly similar 90 to that occurring with the use of either of the other modifications illustrated and previously described.

95 It will be understood without specific illustration that means similar to those shown in Figure 5, and Figures 6 and 7, may be independently mounted and operated at the same speed as the band wheel by means of a suitable connection therewith.

100 As a number of other modifications may be made, by which the circuit may be completed during a portion of the drilling cycle by completing a circuit through a moving bar of the drilling rig without departing from the spirit of the present invention, the scope of the invention is to be restricted only by the limitations contained in the appending claims.

105 What I claim is:

1. In combination with a well drilling rig 110 and an internal combustion engine for actuating the same, electrical means controlled by a moving part of the drilling rig for regulating the speed of the engine.

2. In combination with a well drilling rig 120 and an internal combustion engine for actuating the same, mechanical means for regulating the speed of the engine, and electrical means controlled by a moving part of the drilling rig for actuating said speed 125 regulating means.

3. In combination with a well drilling rig and an internal combustion engine for actuating the same, a solenoid for operating the throttle of the engine, and electrical 130

connections arranged to automatically energize said solenoid during a portion of each operating cycle of the drilling rig.

4. In combination with a well drilling rig 5 and an internal combustion engine for actuating the same, a solenoid for operating the throttle of the engine, an electrical circuit for energizing said solenoid, and means carried by a moving part of the drilling rig 10 for completing said circuit during a portion of each operating cycle of the drilling rig.
5. In combination with a well drilling rig and an internal combustion engine for actuating the same, mechanical means for regulating the speed of the engine, electrical means for operating said mechanical speed regulating means, an electrical circuit to said electrical operating means, and means carried by a moving part of the drilling rig 15 for completing said circuit during a portion of each drilling cycle of the rig.
6. In combination with a well drilling rig and an internal combustion engine for actuating the same, a solenoid for operating the throttle of the engine, an electrical circuit for energizing said solenoid, and means carried by the band wheel of the drilling rig 20 for completing said circuit during a portion of each revolution of the band wheel.
7. In combination with a well drilling rig and an internal combustion engine for actuating the same, mechanical means for regulating the speed of the engine, electrical means for operating said mechanical means, 25 an electrical circuit to said electrical operating means, and means carried by the band wheel of the drilling rig for completing said circuit during a portion of each revolution of the band wheel.
8. In combination with a well drilling rig 30
- 40

and an internal combustion engine for actuating the same, a solenoid for operating the throttle of the engine, an electrical circuit having free terminals adjacent the band wheel of the drilling rig, conducting means 45 carried by the band wheel and arranged to electrically connect said terminals, and insulating means associated with the band wheel and arranged to break such connection during a portion of each revolution of 50 the band wheel.

9. In combination with a well drilling rig and an internal combustion engine for actuating the same, electrical means for regulating the speed of the engine, and means 55 associated with the band wheel of the drilling rig for causing energization of said electrical means during a portion of each revolution of the band wheel.

10. In combination with a well drilling rig 60 and an internal combustion engine for actuating the same, mechanical means for regulating the speed of the engine, electrical means for operating said mechanical means, 65 an electrical circuit to said electrical actuating means having free terminals adjacent the band wheel of the drilling rig, conducting means carried by the band wheel and arranged to electrically connect said terminals, and insulating means carried by 70 the band wheel and arranged to break such connection during a portion of each revolution of the band wheel.

In witness whereof, I hereunto set my hand.

CLARK F. RIGBY.
